(57) **CLAIM**

The ornamental design for a marker light lens, as shown and described.

DESCRIPTION

FIG. 1 is a left side front perspective view of the marker light lens design;

FIG. 2 is a right side front perspective view of the marker light lens design;

FIG. 3 is a right side rear perspective view of the marker light lens design;

FIG. 4 is a left side rear perspective view of the marker light lens design;

FIG. 5 is a front plan view of the marker light lens design;

FIG. 6 is a rear plan view of the marker light lens design;

FIG. 7 is a left side elevation view of the marker light lens design;

FIG. 8 is a right side elevation view of the marker light lens design;

FIG. 9 is a top end plan view of the marker light lens design; and,

FIG. 10 is a bottom end plan view of the marker light lens design.

In the drawings, the broken line disclosures depicting attachment prongs form no part of the claimed design.

1 Claim, 4 Drawing Sheets
